PROPS, ESPECIALLY FOR USE IN COAL MINES

Bernard Tebb, Swanland, and Clarence Herbert Perry, Hull, England, assignors to Mastabar Mining Equipment Company Limited, Hull, England, a British company

Application June 8, 1956, Serial No. 590,185

Claims priority, application Great Britain June 10, 1955

14 Claims. (Cl. 121—40)

The present invention concerns hydraulic pit props for mine roof supporting or shoring purposes.

An object of the invention is to provide a prop of generally improved structure and performance which is especially suitable for filling the requirements in coal mines where, for example, a controlled roof collapse may be necessary.

Another object is to provide for effecting collapse of the hydraulic pit prop from a safe distance.

A further object is to enable the collapsing pressure to be selected by an external adjustment on the prop.

To achieve the first of these objects the present invention provides a hydraulic prop having a rising characteristic as regards its load releasing behaviour. Such rising characteristic implies that an initial release will take place on the attainment of a minimum predetermined loading and that the loading to cause subsequent releases will increase with load displacement until the value of the load becomes equal to the maximum load sustaining capacity of the prop.

Frictional or mechanical props, which may be at a disadvantage compared with hydraulic props on account of greater weight or fire hazard, have indeed been constructed with rising characteristics; whereas hydraulic props have hitherto allowed release of the load at a substantially constant liquid pressure irrespective of load displacement, thus having a flat characteristic.

According to the present invention therefore a rising characteristic hydraulic prop incorporates a liquid pressure relief valve adapted to open at a variable pressure and a relief pressure adjuster actuated responsive to a function of load displacement. The adjuster preferably acts on the relief valve spring and may constitute or provide a displaceable spring adjustment or anchorage.

Thus the relief valve on a first portion of the prop may be urged towards its seat by a spring, for example in the form of a torsion bar anchored on the fulcrum of a lever constituting the adjuster, a second portion of the prop displaceable relative to the first portion carrying a cam adapted on displacement occurring to swing the lever and thereby effect rotation of the anchor end of the swing.

Instead of the adjuster being moved mechanically responsive to displacement it may be displaced hydraulically, for example, constituting part of a chamber of variable volume which is expanded by admission thereto of liquid discharged past the relief valve itself.

According to a further feature of the invention a torsion spring loading a relief valve or valves is anchored to a spring loaded member presenting an attachment for an external operating element such as a lanyard. Then on displacement of the member against its spring loading the relief valve loading may be reduced, so as to initiate collapse of the prop.

The position of the spring loading member is preferably adjustable, i.e. by a screwed stop or collar so as to enable the loading of the torsion spring on the relief valve and hence the normal collapsing load to be varied.

The torsion spring may provide positive loading for one relief valve and secondary loading for a second relief valve.

The invention will be described further with reference to the accompanying drawings in which:

Fig. 1 is a medial vertical section of a hydraulic pit prop constructed in accordance with the invention;

Fig. 2 is an elevation of the adjustable release control shown in Fig. 1;

Fig. 3 is an enlarged fragmentary horizontal section on the line III—III of Fig. 1;

Fig. 4 is a part medial vertical section of a portion of an alternative form of hydraulic pit prop constructed in accordance with the invention;

Fig. 5 is a medial vertical section of a modification of the prop shown in Fig. 4;

Fig. 6 is a medial vertical section showing a further form of hydraulic pit prop in accordance with the invention;

Fig. 7 is a horizontal section on the line VII—VII of Fig. 6; and

Fig. 8 is a horizontal cross section on the line VIII—VIII of Fig. 6 certain parts being similar to those shown in Fig. 3.

25 In the drawings like reference numerals refer to like parts.

In the prop shown in Figs. 1 to 3, embodying a mechanically displaced adjuster, an upper or first portion 11 includes a hollow piston or ram 12 attached at its lower end and received within a cylinder forming the lower or second prop portion 14 fixed to the base 15 of the prop. The upper telescopic member 11 is secured at its upper end by way of a collar 16 to an upper extension 17 which, at its upper end, is fixed to the head 18 of the prop.

The inverted piston head 12 includes a chamber 43 formed therewithin by a screwed plug 44 engaged in a threaded and counterbored inverted bore in the piston 12. The plug 44 is provided with an oil sealing or packing ring 44a, and its lower end is flanged so as to engage and retain an end plate 45 which serves to retain an oil seal 13. The chamber 43 communicates with the interior of the upper telescopic member 11 which constitutes an oil reservoir, by way of a bore 47. A space 50, below the piston 12, within the telescopic member 14 communicates with the chamber 43 by way of a vertical bore 55 which runs into a horizontal bore 56. A ball relief valve 57, displaceable within the bore 56 is adapted, in its closed position, to prevent entry of oil from the space 50 to the chamber 43.

The ball 57 is urged towards its seating 58 by a pressure bar 62 projecting radially from near the lower end of a vertically extending spring torsion bar 61 suitably guided at or near both its ends for rotary movement relative to the piston 12. The upper end of the torsion bar 61 is attached at one end of an arm 64 and thus by reason of its guiding this end of the bar 61 with the arm 64 constitutes a lever fulcrum. The other end of the arm 64 projects outwardly through a slot 80 in the wall of the upper extension 17 of the upper prop portion 11 and bears on a tapered face of a vertically extending cam bar 73 attached near its lower end to the outer surface of the lower portion 14 of the prop. The vertical position of the cam bar 73 relative to the lower portion 14 of the prop is adjustable; vertical slots 73a are provided in the cam bar 73 for a clamp 74, in order to permit of adjustment of the initial spring pressure.

An inlet connection (not shown) is provided to the space 50, thus with any suitable preloading of the prop in its initial or maximum height condition, liquid may be pumped into this space 50 of the cylinder.

In the alternative form of construction shown in Fig. 4

hydraulic displacement of the adjuster is effected by making the adjuster in the form of a floating piston 81 displaceable within the piston skirt or hollow cylindrical part of the upper portion 11 of the prop. This floating piston 81 then forms the upper wall of a chamber 82 of variable volume constituted by the space within the lower part of the upper portion of the prop, i.e. between the floating piston 81 and the upper surface of the inverted head of the prop piston 12. A relief valve 83 is arranged to discharge liquid into the variable volume 10 chamber 82 with the result that the floating piston 81 is moved upwardly relative to the piston head 12. The relief valve 83 is disposed within the piston head 12 and is adapted to move downwardly to open and is loaded by a coiled tension spring 84 anchored at its upper end to the floating piston 81. Thus after discharge of liquid from the relief valve 83 the floating piston 81 rises and increased tensional spring pressure is applied to the valve 83.

Alternatively, as shown in Fig. 5, a coiled compression spring 85 is contained in the space 86 between the uppermost interior part of the upper portion of the prop and the floating piston 81, its lower end resting on an abutment 87 which bears downwardly on an upwardly opening relief valve 83 in the floating piston 81. This valve 83 is connected to a passage 88 through the prop piston head 12 by way of a high pressure coiled flexible conduit 89. Hence on liquid being discharged by the valve 83, downwardly into the chamber 82 below the floating piston 81, the floating piston 81 rises carrying the relief valve 83 with it. This upward displacement of the floating piston 81 or adjuster provides a relative displacement of the abutment 87 of the upper end of the coiled compression spring 85 which is thereby compressed so as to increase the pressure exerted on the relief valve 83.

In both these hydraulic arrangements a low pressure subsidiary relief valve 90 discharging upwardly is provided to relieve excessive pressure developing below the floating piston 81. External connections both to the prop, or high pressure cylinder and to the chamber of variable volume or low pressure cylinder are provided to enable the prop to be appropriately preloaded on its initial installation.

In the embodiment shown in Figs. 6 to 8, a hydraulic pit prop includes an upper telescopic member 11 having a piston 12 attached to its lower end. The piston carries a sealing ring 13 adapted to seal the piston in liquid tight manner within a cylinder constituted by a lower telescopic member 14 fixed to the base 15 of the prop.

The upper telescopic member is secured at its upper end by way of a collar 16 to an upper extension 17 which at its upper end is fixed to the head 18 of the prop.

A pump cylinder 21 is fixed in a screwed bore at the top of the piston 12. In this cylinder a large piston 22 is displaceable. The large piston 22 is axially bored to accommodate a piston rod 23 and counterbored to form a smaller diameter pump cylinder 24 within which a small piston 25 fixed to the lower end of the piston rod 23 is displaceable. The upper end of the piston rod is fixed in a clevis 26 which is urged upwardly relative to the large pump piston 22 by a coiled compression spring 27. A connecting rod 28 is pivoted at its lower end to the clevis by means of a pin 29, and its upper end is pivotally connected to a crank 30 adapted to be rotated by application of a suitable hand tool to the squared outer end 31 of its shaft 32 which is journalled in a socket 33 secured in the wall of the extension 17. Suitable oil sealing or packing rings are provided on the pump pistons 22 and 25 and on the pump crank shaft 32.

The working space of the pump cylinders communicates by way of an inlet ball valve 41 and a bore 42 with an enclosed chamber 43 formed within the prop

5 piston 12 by a screwed plug 44 engaged in a threaded and counterbored inverted bore in the prop piston 12. This plug 44 is provided with an oil sealing or packing ring, and its lower end is flanged so as to engage and retain an end plate 45 which serves to retain the oil seal 13 and provide an abutment for the spring of an outlet valve 46.

The chamber 43 communicates with the interior of the upper telescopic member 11 which constitutes an oil reservoir, by way of a bore 47. The working space of the pump pistons communicates by way of a bore 48, the outlet valve 46 and an aperture 49 in the plate 45 with a space 50, below the piston 12, within the lower telescopic member 14.

15 The space 50 communicates with the chamber 43 by way of a vertical bore 51 which runs into a horizontal bore 52. A release valve 53 is urged on to a seating, which results from a change in diameter of bore 52, by a coiled compression spring 54. Space 50 further 20 communicates with the chamber 43 by way of a vertical bore 55 which runs into a horizontal bore 56. A relief valve 57 slidable within bore 56, is urged against a seating 58 within bore 56 by means of a vertically extending torsion bar spring 61 which passes downwardly through a bore in the prop piston 12 into the chamber 43 where its lower end is fixed to an arm 62 into which one end of the relief valve 57 is recessed. Arm 62 has a projecting 25 striker 63 adapted to bear against the valve 53 on rotation of torsion bar spring 61.

The upper end of the torsion spring is fixed to an arm 30 64 which is pivotally connected to a link 65 which in turn is pivotally connected to a lug 66 of a plunger 67. This plunger is displaceable in a cylindrical housing 68 containing a spring 69 which bears against an adjustable 35 abutment plug 70 and urges the plunger in an inward direction. The shank of the plunger passes outwardly through a bore in the plug 70 and is screwed into an eye 71. A lanyard for effecting release of the prop may be passed through the aperture in the eye 71; or alternatively, as shown a rod 72 is fitted into this aperture and arranged to engage a wedge ended cam or release bar 73. This bar 30 40 45 50 55 60 65 70 75 73 is adjustable in a vertical direction relative to the lower telescopic prop member 14 by means of a clamp 74 so as to enable the cam profile to cause outward displacement of the plunger to a required extent in a given relative position of the two telescopic members 11 and 14 of the prop.

In operation the prop is extended by manually imparting rotation to the shaft 31 using an appropriate brace or other tool engaged on the squared end of this shaft. Rotation of the shaft 31 causes the crank 30 to impart vertical reciprocation to the small piston 25 by way of the connecting rod 28, pin 29, clevis 26 and piston rod 23. At first the liquid pressure in the pump cylinder 21 is relatively low and the large piston 22 is reciprocated with the small piston 25. This results in a rapid displacement of oil from the reservoir, through the bore 47 into chamber 43 and through the bore 42 and past valve 41 into the pump cylinder 21 and thence through the bore 48, past valve 46 and through the aperture 49 into the space 50, with the result that the upper member 11 is forced outwardly, thereby extending the prop. When, however, the head 18 bears against the mine roof the pressure within the space rises rapidly and further rotation of the shaft 31 causes the small piston 25 to move relative to the large piston 22 as soon as the upward thrust due to liquid pressure on the large piston 22 exceeds the downward thrust exerted upon it by the spring 27. Continued pumping action is then effected by reciprocation of the small piston 25 which thus enables a preloading pressure to be applied with relatively small liquid displacement to the space 50 and thereby to the prop as a whole.

60 65 70 75 80 85 90 95 Torsion bar spring 61 is initially adjusted to maintain valve 57 against seating 58 by means of adjustable plug 70. Excessive pressure within space 50 unseats valve

57 and oil flows from space 50 to the reservoir via bores 55, 56, chamber 43 and bore 47 causing collapse of the prop (or less rapid extension). The unseating of valve 57 is assisted by outward movement of plunger 67 causing rotation of torsion bar spring 61 and arm 62. Further outward movement of plunger 67 causes striker 63 to unseat valve 53 and oil flowing from space 50 to the reservoir is provided with an additional path via bores 51, 52, chamber 43 and bore 47.

Outward movement of plunger 67 is effected by pulling on the eye 71 by means of a lanyard or other external operating element or is effected automatically during extension of the prop by means of the wedge ended cam 73. It will be appreciated that the wedge ended cam will also cause inward movement of plunger 67 during collapse of the prop, thus progressively increasing the resistance of the prop to collapse.

We claim:

1. In a hydraulically extensible pit prop having a rising characteristic, hydraulic load sustaining means, pressure relief means adapted on opening to relieve hydraulic pressure within said load sustaining means, and relief pressure adjusting means bearing on said pressure relief means and defining a range of relief pressures at which said pressure relief means is permitted to open, said adjusting means being operable responsive to a function of load displacement to render said relief pressure continuously variable within said range during extension and contraction of said prop.

2. A hydraulically extensible pit prop comprising an upper telescopic member, a lower telescopic member, one of said members acting as a piston and being displaceable in a hydraulic cylinder constituted by the other of said members, a liquid pressure relief valve communicating with said cylinder and adapted to open to relieve hydraulic pressure therein, and relief pressure adjusting means bearing on said relief valve and defining a range of relief pressures at which said valve is permitted to open, said adjusting means being operable responsive to a function of load displacement to render said relief pressure continuously variable within said range during relative movement between said telescopic members.

3. In a hydraulically extensible pit prop having first and second relatively displaceable portions, a relief valve on said first portion, spring means for urging said relief valve into its closed condition, an adjusting means carried by said first portion and constituting a displaceable anchorage for said spring means, and cam means on said second portion adapted to displace said adjusting means and thereby vary the pressure exerted by said spring means on said relief valve responsive to the relative positions of said first and second portions.

4. In a hydraulically extensible pit prop having first and second relatively displaceable portions, a relief valve on said first portion, a torsion bar spring for urging said relief valve into its closed condition, a lever carried by said first portion and connected at its fulcrum to said torsion bar spring so as to constitute a displaceable anchorage for said spring, and cam means on said second portion adapted to displace said lever and thereby vary the pressure exerted by said torsion bar spring on said relief valve responsive to the relative positions of said first and second portions.

4. In a hydraulically extensible pit prop having first and second relatively displaceable portions, a relief valve on said first portion, a torsion bar spring for urging said relief valve into its closed condition, a lever carried by said first portion and connected at its fulcrum to said torsion bar spring so as to constitute a displaceable anchorage for said spring, and cam means on said second portion adapted to displace said lever and thereby vary the pressure exerted by said torsion bar spring on said relief valve responsive to the relative positions of said first and second portions.

5. In a hydraulically extensible pit prop having first and

second relatively displaceable portions, a relief valve on said first portion, spring means for urging said relief valve into its closed condition, a displaceable wall in said first portion defining therein a chamber of variable volume, 5 said wall being displaced in accordance with the amount of liquid contained in said chamber and constituting a displaceable anchorage for said spring means, and conduit means for feeding hydraulic liquid discharged by said relief valve into said chamber to thereby vary the pressure exerted on the relief valve by said spring means responsive to the relative positions of said first and second portions.

6. In a hydraulically extensible pit prop formed with a reservoir for hydraulic fluid and a working chamber into 15 which said fluid is intended to be urged under pressure to extend said prop, a torsion bar spring, at least one fluid pressure controlling valve communicating with said working chamber loaded by means of said torsion bar spring, said valve controlling the discharge of pressure fluid from said working chamber, a spring loaded displaceable member to which said torsion bar spring is anchored, means acting on said displaceable member for displacing said member between fixed limits during extension and contraction of said prop, the displacement of said member thereby varying between upper and lower limits, the load exerted by said torsion spring on said controlling valve, and an external operating means attached externally to said spring loaded displaceable member and by which said member is displaced to cause the load exerted 20 on the valve by the torsion bar spring to be removed for collapse of the prop.

7. A structure according to claim 6, in which said spring-loaded member is adjustable.

8. A structure according to claim 6, in which said 35 spring-loaded member is adjustable by means of a screwed stop.

9. A structure according to claim 6 in which the fluid pressure control valve is a pressure relief valve, and said structure further comprises at least one further relief valve, the torsion bar spring providing positive loading for one relief valve, and negative loading for the other relief valve.

10. In a hydraulically extensible pit prop having an upper portion and a lower portion, said upper portion being 45 formed with a chamber constituting a reservoir for hydraulic fluid and said lower portion being formed with a chamber constituting a work chamber into which hydraulic fluid is intended to be urged to extend the prop, a piston displaceable in the chamber presented by said 50 lower prop portion, a relief valve carried by said piston and controlling communication between said lower chamber and that presented by the upper prop portion, a vertically extending torsion bar spring having an upper end and a lower end, guide means adjacent to and guiding said 55 ends for rotation of said torsion bar spring relative to said upper prop portion, means for adjustably anchoring the upper end of said spring against rotation relative to said upper prop portion, and an arm fixed to said spring at the lower end thereof and adapted to transmit the spring 60 pressure to said valve to urge it towards its closed condition in opposition to the fluid pressure in the lower chamber.

11. A structure according to claim 10 including a second arm fixed to the upper end of the spring perpendicularly thereto, the upper prop portion being slotted to permit said second arm to extend horizontally outwardly therethrough, and a cam-bar carried by the lower prop portion and adapted to bear on said second arm and vary its angular position relative to the prop in accordance with the relative positions of said upper and lower prop portions.

12. In a hydraulically extensible pit prop having two relatively displaceable portions, a hydraulic pressure relief valve carried by one of said portions, a torsion spring loading said valve, an anchorage member connected to

said spring and displaceably mounted on said portion carrying the relief valve, an external operating member for displacement of said anchorage member and an attachment for said external operating member whereby said valve may be caused to open by displacement of said anchorage member and consequential variation in the loading applied to said valve by said torsion spring.

13. In a hydraulically extensible pit prop having a continuously varying rising characteristic as regards its load releasing behaviour, hydraulic load sustaining means, pressure relief means adapted on opening to relieve hydraulic pressure within said load sustaining means, and hydraulically displaced relief pressure adjusting means for varying the hydraulic pressure at which said relief means opens responsive to a function of the amount of hydraulic liquid discharged by said relief means.

14. A hydraulically extensible pit prop comprising an upper telescopic member, a lower telescopic member, one

of said members acting as a piston and being displaceable in a hydraulic cylinder constituted by the other of said members, a liquid pressure relief valve communicating with said cylinder and adapted to open at a variable pressure, and hydraulically displaced relief pressure adjusting means acting on said relief valve responsive to a function of the amount of hydraulic liquid discharged by said valve whereby to provide a rising characteristic in the load-displacement behaviour of the prop.
